UNITED STATES PATENT OFFICE.

DANIEL ARCHIE DASHER, OF RIVERTON, ILLINOIS.

POSTHOLE-DRILLING MACHINE.

Application filed October 20, 1920. Serial No. 418,136.

To all whom it may concern:

Be it known that I, DANIEL A. DASHER, a citizen of the United States, residing at Riverton, in the county of Sangamon, State of Illinois, have invented a new and useful Posthole-Drilling Machine; and I do hereby declare the following to be a full, clear, and exact description of the invention, such as will enable others skilled in the art to which it appertains to make and use the same.

The invention relates to post hole drilling machines and has for its object to provide a device of this character comprising a wheel supported platform, on which platform an engine is mounted, power from said engine being utilized to rotate a horizontally disposed shaft mounted in bearings of the framework carried by the platform. Also to provide a vertically disposed auger rotating bar, which bar is threaded and has its threaded portion slidably mounted in a block, said threaded portion being in mesh with a worm gear carried by the block, which worm gear allows the threaded bar to be fed downwardly as it rotates, said worm gear also forming means whereby the increased downward feeding of the threaded bar may be obtained or the bar raised as a whole. Also to provide a feathered gear on the upper end of the threaded bar, which gear meshes with a gear carried by the horizontally disposed shaft.

A further object is to provide plumbing means whereby the proper level of the machine may be obtained before starting a boring operation.

With the above and other objects in view the invention resides in the combination and arrangement of parts as hereinafter set forth, shown in the drawings described and claimed, it being understood that changes in the precise embodiment of the invention may be made within the scope of what is claimed without departing from the spirit of the invention.

In the drawings:

Figure 1 is a side elevation of the machine, parts being broken away to better show the structure.

Figure 2 is a front elevation of the machine.

Referring to the drawings, the numeral 1 designates a platform which platform is provided with U-shaped brackets 2 in which are slidably mounted blocks 3. The blocks 3 have pivoted thereon the supporting

wheels 4, which wheels are utilized for moving the machine from place to place. By pivotally mounting the wheels 4 on the blocks 3 the level of the platform 1 may be varied as desired. The varying of the level being accomplished by means of dogs 5, which cooperate with the teeth 6 of the blocks 3. The dogs 5 are provided with handle members 7 by means of which handle members the dogs may be forced out of engagement with the teeth 5.

Rising upwardly from a substantially central position of the platform 1 is a framework 8 in bearings 9 of which is rotatably mounted a horizontally disposed drive shaft 10. One end of the drive shaft 10 has secured thereto as at 11 a drive pulley 12 and also an idle pulley 13. Extending around the drive pulley 12 and the pulley 14 of an engine 15 is a belt 16 by means of which belt the drive pulley 12 is rotated and consequently the shaft 10 also rotated. Engine 15 is disposed on the platform 1 and is preferably an internal combustion engine.

Secured to one end of the shaft 10 is a bevel gear 16^a, which bevel gear meshes with a bevel gear 17 which is slidably mounted on the portion 18 of the auger carrying screw 19. The portion 18 of the auger carrying screw is slidably mounted in a bearing 20 of a bracket 21 and is also slidably mounted in the bevel gear 17. As the gear 17 is rotated the auger carrying screw 19 is also rotated. Screw 19 is provided with a threaded portion 22, which threaded portion meshes with a worm gear 23. The worm gear 23 is normally stationary and as the auger screw 19 rotates it will be seen that the screw will be fed downwardly in the bearing 24 of the bearing block 25. The lower end of the auger screw 19 is provided with chuck 26, in which chuck the shank 27 of an auger 28 is secured. It will be seen that as the feeding screw 19 rotates that the auger 28 will be forced downwardly into the ground.

This feeding may be increased or retarded in speed by rotating the worm gear 23 which has secured to its shaft 29 a sprocket 30, said sprocket being connected to a sprocket 31 by means of a sprocket chain 32. When it is desired to control the downward feeding of the threaded bar 19, a handle 33 is placed on the sprocket 31 by means of which handle a sprocket 31 is rotated, which action will cause the worm gear 23 to rotate, said rotation being according to the direction it is

- desired to move the threaded bar 19. It will be seen that a drilling mechanism is provided wherein the downward feeding of the bar 19 may be minutely varied no matter 5 how fast the screw is rotated. It will also be seen that by rotating the worm gear 23 that the auger may be raised from the hole 34 as desired and even when the screw bar 19 is rotated.
- 10 Secured to the sides of the framework 4 as at 35 are plumb lines 36, to the lower ends of which are secured plumb bobs, said plumb bobs forming means whereby the level of the platform 1 may be easily established and 15 raised to a horizontal plane by means of the slideable blocks 3 and dogs 5.

The invention having been set forth what is claimed as new and useful is:—

- 10 A post hole drilling machine comprising a 20 wheel supported platform, a framework carried by said platform, a rotatable feeding screw rotatably mounted in bearings carried by the framework and also slidably mount-

ed in said bearings, said feed screw having a threaded portion and a non threaded portion, a horizontally pivoted worm gear meshing with the thread of the threaded portion of the feed screw, means for rotating said worm gear for raising and lowering the screw independent of rotation of the screw, 25 a bevel gear feathered on the unthreaded portion of said feed screw, a horizontally disposed shaft rotatably mounted in the framework, a bevel gear mounted on the horizontally disposed shaft and meshing 30 with said beveled gear, an engine located on the platform and belt and pulley connections between said engine and the horizontally disposed framework carried shaft.

In testimony whereof I have signed my 40 name to this specification in the presence of two subscribing witnesses.

DANIEL ARCHIE DASHER.
